UNITED STATES PATENT OFFICE.

WILLIAM R. CHISHOLM, OF PITTSBURG, PENNSYLVANIA.

METAL AND CONCRETE POLE OR POST.

964,491.

Specification of Letters Patent.

Patented July 19, 1910.

Application filed August 16, 1909. Serial No. 513,070.

To all whom it may concern:

Be it known that I, WILLIAM R. CHISHOLM, a resident of Pittsburgh, in the county of Allegheny and State of Pennsylvania, have invented a new and useful Improvement in Metal and Concrete Poles or Posts, of which the following is a specification.

This invention relates to metal and concrete posts and poles, and more particularly 10 to light posts and poles for various purposes.

The invention relates to that class of metal post or pole provided with a concrete base to be buried in the ground which not 15 only imparts stability to the post or pole but also prevents the same from rusting or corroding.

The object of the invention is to provide 20 a construction to facilitate the molding of the concrete around the base of the pole and which also protects the concrete during handling and shipping.

The invention comprises the arrangement 25 and construction of parts hereinafter described and claimed.

In the accompanying drawing Figure 1 is a side view of a post or pole embodying 30 the invention; Fig. 2 is a vertical section through the base on an enlarged scale; and Fig. 3 is a horizontal section taken just above the bottom portion of the base.

The post or pole proper, that is, the shaft, is shown at 1. This may be of any suitable 35 construction, shape or size, being shown as a metal tube. Around the lower end of this tube is molded a concrete base 2 of sufficient length and size to form a suitable anchorage 40 for the post in the ground. The mass of concrete is surrounded by a metal casing 3 which may be of any suitable shape in cross-section, preferably circular, as shown, and with the edges of the sheet suitably united, such as by riveting, shown at 4, although 45 an ordinary crimped or seamed joint such as used in stove pipe construction may be used. The casing has secured therein a

wooden bottom 5 of circular form which is held in position by means of nails or similar members 6 driven through the casing 50 into the edges of the board. This wooden bottom has formed centrally therein in its upper surface a socket 7 in which the lower end of the shaft 1 is set, said socket extending only part way through the bottom. The casing 3 may be of any suitable material,

preferably of metal construction, such as metal mesh, but preferably of thin sheet metal.

In constructing the pole the casing 3 is formed and the bottom 5 is secured therein. 60 The shaft 3 then has its lower end inserted in the socket 7 in the bottom, after which the concrete 2 is filled into the casing around the shaft and firmly rammed in place. When the concrete sets it binds firmly together the shaft and casing. The casing 3 serves as the mold for shaping the concrete base and at the same time forms a protecting casing around the concrete so that the latter cannot accidentally crack, chip or 65 break in handling or while being shipped.

In use the pole is sunk into the ground practically to the top of the concrete base. The concrete base is of such size and length as to give the necessary stable anchorage in 75 the ground and also prevents rusting of the metal post. The metal casing 3 is preferably coated outside with asphaltum or similar coating material to enhance its appearance, and which also to some extent prevents 80 the same from rusting when in the ground, although the latter is not necessary as no harm is done even if said casing rusts entirely away after the post or pole is put into the ground.

By use of the casing the formation of the base is expedited and bases of uniform shape and size produced. At the same time the pole or post can be quite severely handled in shipping or the like without danger of injuring the concrete base.

What I claim is:

1. As an article of manufacture, a post or pole comprising a metal shaft, a sheet metal mold and protecting casing surrounding the 95 end of the shaft and provided with a bottom having a seat for the end of the shaft, and concrete filling the space between said casing and shaft.

2. As an article of manufacture, a post or 100 pole comprising a metal shaft, a sheet metal mold or casing surrounding the end of said shaft, a bottom for said mold or casing provided with a socket for the end of the shaft, and concrete filling the space between the 105 mold or casing and shaft.

3. As an article of manufacture, a post or 110 pole comprising a metal shaft, a metal mold or casing surrounding the end of the shaft, a wooden bottom secured in said casing and

22
provided with a socket for the end of the shaft and cementitious material between the mold or casing and the shaft.

4. As an article of manufacture, a post or
5 pole comprising a metal shaft, a thin light
strong mold or protecting casing surround-
ing the end of the shaft, a bottom secured in
said mold or casing provided with a socket
for the end of the shaft, and concrete fill-
10 ing the space between the mold or casing and
the shaft.

5. As an article of manufacture, a post or

pole comprising a metal shaft, a sheet metal
mold or casing surrounding the end of the
shaft, a bottom secured in said casing and 15
provided with a socket for the end of the
shaft, and cementitious material filling the
casing around said shaft.

In testimony whereof, I have hereunto set
my hand.

WILLIAM R. CHISHOLM.
